DETACHABLY COUPLED END STOP

Davis Marinsky, Bronx, N. Y., assignor to White-hall Patents Corporation, New York, N. Y., a corporation of New York

Application May 8, 1936, Serial No. 78,604

15 Claims.

(CL 24—205)

This invention relates to separable fasteners employing stringers having coupling elements with a slider movable along the stringers to couple and uncouple said elements, and particularly to devices of this class employing detachably coupled end stops at one end of the fastener stringers whereby said stringers may be separated to adapt the fasteners to uses requiring the entire separation of the stringers thereof; and the object of the invention is to provide an end stop of the class described including a yielding portion adapted to be engaged by the slider to control the coupling and uncoupling of one of the stringers in the operation of attaching and detaching said stringers; a further object being to provide an end stop, the yieldable element of which also serves to support and maintain the slider in engagement with the end stop when the stringers are separated in order to maintain the slider in position to facilitate recoupling of the stringers whenever desired; a still further object being to provide a detachably coupled end stop wherein the yieldable part of said stop and a companion coupling part of one stringer are provided one with a recess or channel, and the other with a projection entering the channel to maintain said parts against relative longitudinal movement when coupled together, with other means for retaining said parts against lateral displacement with respect to each other; and with these and other objects in view, the invention consists in a device of the class and for the purpose specified, which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a plan view of one end portion of a separable fastener showing one method of carrying my invention into effect.

Fig. 2 is a partial section on the line 2—2 of Fig. 1.

Fig. 3 is a partial section on the line 3—3 of Fig. 1.

Fig. 4 is a perspective view of one part of the device, detached.

Fig. 5 is a view similar to Fig. 1 showing a modification, and omitting one of the stringer parts.

Fig. 6 is a partial section on the line 6—6 of Fig. 5.

Fig. 7 is a perspective view of a part of the construction shown in Fig. 5.

Fig. 8 is a partial section on the line 8—8 of Fig. 5; and,

Fig. 9 is a view similar to Fig. 8 showing a modification and showing part of the coupling bar diagrammatically in section.

In Fig. 1 of the drawing, I have indicated one end portion of a separable fastener employing stringers 10, 11, each having coupling links or elements 12, 12a, attached to one edge portion thereof and spaced longitudinally of the stringers whereby the stringers may be coupled and uncoupled by a suitable slider 13 movable longitudinally of the stringers as in other devices of this kind.

In the construction shown in Fig. 1, I have illustrated reinforcing coupling plates 14, 14a attached to the ends of the stringers, but it will be understood that these plates may or may not be employed, depending entirely upon the use of the separable fastener. Each of the plates 14, 14a includes parts 15 extending around the adjacent edges 10a, 11a of the stringers, which in the construction shown are beaded. The plates are arranged on the upper and lower surfaces of the tapes 10 and 11 and are secured in position by end flanges 16 and prongs 17. Secured to each beaded edge 10a, 11a of the tapes 10 and 11 and upon the portions 15 of the plates 14 and 14a are elongated coupling bars 18 and 19 which extend beyond the inner ends of the plates 14, 14a. These bars may be made of any suitable material, but are preferably in the form of channel-shaped die castings firmly secured to the tapes 10 and 11.

At 20, I have shown a coupling body which is substantially U-shaped in form in longitudinal section, the top wall 21 being longer than the bottom wall 22, and the crosshead 23 is of such width as to form channels between the walls 21 and 22 for receiving the bars 18 and 19. The projecting portion 21a of the top wall has its free edge rounded, and this projection is slightly flared upwardly so as to permit free movement of the slider beneath the projection 21a in order to raise a projection or pin 24 on the wall 21, 21a out of engagement with a recess 25 formed in the bar 18. The construction 24, 25 provides means for keying or retaining the bar 18 against displacement from the channel of the coupling body 20.

The side edges of the bottom wall 22 of the body 20 are turned upwardly as indicated at 22a

- to form retaining flanges, one of which guides the bar 18 in its movement into the channel and retains the same against lateral movement with respect to the body 20, whereas the bar 19 rests against the other flange 22a, said bar being secured to the body 20 by riveting or in any other desired manner as indicated at 26. The free end 22b of the wall 22 forms a stop limiting the movement of the slider in the direction of the body 20.
- 10 In Figs. 5 to 8 inclusive, I have shown a slight modification in the construction which consists in substituting for the body 20 a substantially similar body 29, the top wall 30 of which is severed along the line 31, which also extends through the 15 crosshead of the body 29 to form a freely flexing or yielding side portion 32, the front end portion 33 of which is of a width equal to the full width of the body 29 and is separated from the top plate 30 proper by the cut as indicated at 34.
- 20 With this construction, a pin or projection 35 is formed on the yielding part 32, and this part 35 is equivalent to the part 24 and is adapted to enter a recess 25a in a bar 18a similar to the bar 18.
- 25 Aside from the foregoing changes in the construction, the structure shown in Figs. 5 to 8 inclusive is the same as that shown in the other figures, and the same references will indicate like parts in the respective views. It is understood that in Fig. 5 of the drawing, the stringer 10 and its associated parts have been removed to indicate the separation of the stringers and to clearly show that the body 29 is fixedly secured to the strip 11 by the rivet 26a as in the 30 construction shown in Fig. 1. The primary difference between the two figures is that in Fig. 1 of the drawing, the entire top plate 21—21a flexes upwardly, whereas, in the construction shown in Figs. 5 to 8 inclusive, the parts 32—33 35 only of the top plate are flexed upwardly. By extending the cut or severing line 31 over the crosshead, a greater resiliency is provided in the yielding portion.
- With the forms of construction disclosed, in 40 the operation of uncoupling the fastener stringers, the slider is moved in the direction of the end stop. In this operation, the narrow contracted end 13a of the slider extends beneath the yielding portion 21a of the top plate 21 or the part 33 and forward end of the part 32, which operation serves to raise the pin or projection 24—35 45 out of engagement with the recess 25, 25a to permit the free removal of the companion stringer from the end stop body 20—29. In this connection it will also be understood that by reason of the tensional engagement of the yielding portion of the body with the slider, the slider will be maintained in position against the end of the bottom wall so as to facilitate the 50 recoupling of the stringers, in which operation, the bar 18—18a is first passed through the usual channel of the slider and then into the channel of the stop body 20, 29.
- In the operation of drawing the slider away 55 from the body 20, 29, in recoupling the stringers, as partially indicated in Fig. 1 of the drawing, the pin or projection 24—35 will automatically drop into the recess 25, 25a to retain the bar 18—18a against longitudinal movement with respect to the body 20—29. Upon a consideration 60 of Fig. 1 of the drawing, it will be noted that the outer side edge of the bar 18 is preferably beveled to facilitate insertion of the bar into the channel of the body 20. This will also be true of 65 the bar 18a.

In constructing the yieldable wall or wall portions 20, 21—32, 33, the same may be constructed so as to tensionally engage the bar 18 and 18a when the latter is within the body 20, 29 in coupled relation so as to securely and rigidly retain the bar in position and to aid in preventing relative movement of the parts. The several parts of the end stop may be modified as to form and dimensions to suit various kinds and classes of installations, as well as sizes of separable fasteners employed.

In Fig. 9 of the drawing, I have shown a slight modification, and in this figure, I have indicated at 36 the contracted end portion of a slider 13', in other words, similar to the end portion 13a, and the top wall of said end of the slider is provided with a transverse groove 37. At 38, I have shown the top wall of the body portion 29' of a detachable end stop, the free resilient end portion of which is provided with an in-turned flange 39 which is adapted to enter the groove 37 to retain the slider against displacement from the end stop, thus providing a more positive means of retaining said parts together and facilitating the coupling of the end stop parts together. The rounded end 36a of the top wall of the slider will permit the movement of the slider beneath the flange 39 in the operation of raising the resilient top wall 38 to move the pin 40 similar to the pins 24 and 35 into inoperative position or out of the recess 25'. By employing a transverse groove or recess 37 and a relatively wide flange 39, the slider will also be maintained in proper position to facilitate insertion of the other part 18' of the detachable coupling whenever desired.

Having fully described my invention, what I claim as new and desire to secure by Letters Patent, is:

1. A detachably coupled end stop for separable fastener stringers comprising a U-shaped body secured to one side edge portion of a stringer at one end thereof in such manner as to dispose a channeled portion of said body outwardly of said edge of the stringer, said channeled portion having a spring wall having a coupling element thereon, the other stringer having an elongated coupling bar on the edge portion thereof adapted to enter said channeled portion, said coupling bar having means engaged by said coupling element in securing the stringers together, and means for moving said yieldable coupling element out of engagement with said bar to permit withdrawal of the bar from said channeled portion.

2. A separable fastener of the class described comprising stringers adapted to be coupled and uncoupled and a slider movable longitudinally of the stringers to couple and uncouple the same, means at one end of the stringers for coupling said stringers, said means comprising parts secured to each stringer permitting attachment and detachment thereof, said parts having inter-engaging elements for retaining the same against relative movement, and means whereby the movement of the slider into engagement with one of the parts of said coupling means will operate to release said coupling elements to permit attachment and detachment of said parts.

3. A separable fastener of the class described comprising stringers adapted to be coupled and uncoupled and a slider movable longitudinally of the stringers to couple and uncouple the same, means at one end of the stringers for coupling said stringers, said means comprising parts se-

5 cured to each stringer permitting attachment and detachment thereof, said parts having interengaging elements for retaining the same against relative movement, and means whereby the movement of the slider into engagement with one of the parts of said coupling means will operate to release said coupling elements to permit attachment and detachment of said parts, said last named means involving a resilient member.

10 4. A separable fastener of the class described comprising stringers adapted to be coupled and uncoupled, and a slider movable longitudinally of the stringers to couple and uncouple the same, means at one end of the stringers for coupling 10 said stringers, said means comprising parts secured to each stringer permitting attachment and detachment thereof, said parts having interengaging elements for retaining the same against relative movement, means whereby the movement 15 of the slider into engagement with one of the parts of said coupling means will operate to release said coupling elements to permit attachment and detachment of said parts, said last named means involving a resilient member, and said resilient member tensionally engaging the slider to retain the same against accidental displacement on the stringer.

20 5. In separable fasteners of the class described employing stringers adapted to be detachably coupled at one end, one of said stringers being provided at one end with a part secured thereto and including a channeled portion projecting from one side edge of the stringer at said end thereof, one side wall of said channel having a yieldable 25 coupling portion, the other stringer having a part at one end thereof adapted to enter said channel and to be engaged by said yieldable coupling portion in retaining the stringers together, and the free end of said yieldable coupling portion having an inturned flange.

30 6. A separable fastener of the class described comprising stringers adapted to be coupled and uncoupled and a slider movable longitudinally of the stringers to couple and uncouple the same, means at one end of the stringers for detachably 35 coupling said stringers and to limit the movement of the slider in one direction on said stringers, said means comprising interengaging parts, a coupling element for retaining said parts together, and means whereby the movement of the slider into engagement with one of said parts will move 40 said element into position to permit detachment of said parts and the uncoupling of said stringers.

45 7. A separable fastener of the class described comprising stringers adapted to be coupled and uncoupled and a slider movable longitudinally of the stringers to couple and uncouple the same, means at one end of the stringers for detachably 50 coupling said stringers and to limit the movement of the slider in one direction on said stringers, said means comprising interengaging parts, a coupling element for retaining said parts together, means whereby the movement of the slider into engagement with one of said parts will move said 55 element into position to permit detachment of said parts and the uncoupling of said stringers, and said slider having a recess, and a projection on said first named part adapted to enter said recess to retain said part and slider against separation.

60 8. A separable fastener of the class described comprising stringers adapted to be coupled and uncoupled and a slider movable longitudinally of the stringers to couple and uncouple the same, means at one end of the stringers for coupling 65

said stringers, said means comprising parts secured to each stringer, said parts being coupled and uncoupled by relative movement longitudinally one with respect to the other and having interengaging elements for retaining the same against relative movement, and means engaged by the slider when in juxtaposition to said parts permitting coupling and uncoupling of said parts.

9. A separable fastener of the class described comprising stringers adapted to be coupled and uncoupled and a slider movable longitudinally of the stringers to couple and uncouple the same, means at one end of the stringers for coupling said stringers, said means comprising parts secured to each stringer, said parts being coupled and uncoupled by relative movement longitudinally one with respect to the other and having interengaging elements for retaining the same against relative movement, means engaged by the slider when in juxtaposition to said parts permitting coupling and uncoupling of said parts, and interengaging means on one of said parts and said slider for retaining the same against accidental displacement and for maintaining predetermined alignment of said part and slider.

10. A detachably coupled end stop for separable fastener stringers comprising a U-shaped body secured to one side edge portion of a stringer at one end thereof in such manner as to dispose a channel of said body outwardly of said 30 edge of the stringer, said body having a movable coupling part for engaging a member to be coupled therewith, and a portion of said part projecting into the channel of said body.

11. In fasteners employing stringers with a slider movable longitudinally of the stringers to couple and uncouple the same, an end stop at one end of the stringers, means involving interengaging coupling elements on said stop and slider for retaining the slider against detachment from said stop when at the limit of its movement in the direction of said stop, the coupling element of said stop comprising an elongated spring plate, said stop having a channel at one side thereof in which one of the stringers is slidably mounted, and said spring plate having a pin projecting into the channel and adapted to engage the stringer when inserted therein to retain said stringer against displacement.

12. A separable fastener employing stringers adapted to be detachably coupled at one end, said end of the stringers having interengaging parts, one of said parts having a channel arranged outwardly of one side edge of the stringer, the other part being insertable into said channel, said parts being provided one with a movable member and the other with a coupling portion for receiving said member to retain said parts against separation, and means for disengaging said member from the coupling portion to permit detachment of said parts in the separation of said stringers.

13. A separable fastener employing stringers and an end stop at one end of the stringers for detachably coupling said stringers, said end stop comprising a socket part on one stringer and a pin part on the other stringer, a slider for coupling and uncoupling the stringers independent of said end stop parts, interengaging means on the socket part and slider for retaining the slider 70 against displacement from said part when said slider is arranged adjacent said part, and said last named means involving a resiliently supported member on the socket portion of said part and in interlocking engagement with the 75

pin part when inserted into said socket portion.

14. In separable fasteners employing stringers adapted to be coupled and uncoupled, a slider movable longitudinally of the stringers to couple and uncouple the same, an end stop at one end of the stringers, said end stop comprising independent parts secured to the separate stringers, one of said parts having an enlarged body with a channel at one side of said body and ex-

10 tending throughout the length thereof, and the other a pin, one end of which is adapted to enter and to be concealed within the channel of said body in coupling said parts together, said enlarged body having an elongated yieldable por-

15 tion at one side only thereof and forming one outer wall of the channel in said body, said slider being adapted to engage said yieldable walls, and interengaging means on said yieldable wall and on said slider for retaining the

20 slider against accidental movement with respect to the enlarged body of said end stop.

15. In fasteners employing stringers with a slider movable longitudinally of the stringers to couple and uncouple the same, an end stop at one end of the stringers, said end stop comprising detachably coupled pin and socket parts, the 5 socket part being secured to one stringer and the pin part secured to the opposed stringer, the socket part having a channel arranged longitudinally thereof outwardly of said stringer to receive said pin part in coupling the stringers together, the channel of said socket part having a yieldable outer wall, a coupling element on said yieldable wall adapted to engage the slider for retaining the slider against detachment from said socket part when the pin part is detached, 15 and interengaging means on the pin part and the yieldable wall of said socket part for retaining the pin part against displacement from the socket part when the slider is removed from the end stop.

DAVIS MARINSKY.
